WATCHCASE

Oscar Gruber, Minneapolis, Minn.

Application July 20, 1944, Serial No. 545,783

2 Claims. (Cl. 58—105)

My invention relates to a watch case construction in which means is provided for supporting mechanism of the watch so as to floatingly support the watch mechanism in relation to the outer case.

It is a feature to provide an inner case designed to support the watch mechanism within the same and in turn floatingly support the inner case to the outer case with internal resilient means which are normally concealed within the outer case and extend from the inner case to the outer case. The resilient means may be in the form of coil springs, rubber or any resilient material which may be interposed between the inner and outer cases of the watch to floatingly support the watch mechanism to protect it from jar or sharp blows against the outer case.

It is also a feature to provide an inner case in two forms, one of which may be open at the back and closed at the front by the watch dial. In this form, the watch mechanism supported within the inner casing may be inspected by removing the back of the outer case in the usual manner. The second form of the inner case is formed with a closed back and the case is in the form of a cup which is adapted to be closed by the dial at the front, and thus conceal and virtually hermetically seal the mechanism within the inner case.

It is also a feature to provide a floatingly supported inner case positioned within the outer case so that the entire mechanism, including the winding stem, is floatingly supported inside of the outer case. It is also an important feature to provide a simple means for supporting the watch mechanism within the outer case so that all jar or shock is absorbed by the resilient means supporting the mechanism in the outer case, and thus, the delicate working parts of the watch mechanism are cushioned and protected in a manner to give longer life and better timekeeping service by the watch mechanism supported in this manner.

It is a feature to use a small number of operating parts to floatingly support the mechanism in the outer case; also, that the supporting means may be small in size and compact in dimensions so that the outer case of the watch may be made small and compact and yet permitting the providing of resilient means for floatingly supporting the mechanism.

These features, together with other details and objects, will be more fully and clearly hereinafter set forth.

In the drawings forming part of my specification:

Figure 1 is a face view of the watch and case having my construction therein.

Figure 2 is an enlarged view similar to Figure 1 with the front and back portions of the case removed and with the watch mechanism removed from the inner casing.

Figure 3 is a section on the line 3—3 of Figure 1.

Figure 4 is a section on the line 4—4 of Figure 1.

Figure 5 is a section on the line 5—5 of Figure 2.

Figure 6 is a section on the line 6—6 of Figure 1.

Figure 7 illustrates the common ring template showing the same held in position by the stem pin and surrounding the inner watch case, and also showing the drill used for drilling the holes in the inner case spaced slightly from the template.

Figure 8 illustrates the outer watch case with the template ring held in position by the stem pin in the case and the drilling unit in position to drill a hole in the inside of the outer case, the drill being guided by the template.

Figure 9 is a side elevation of the drilling unit removed from the watch case.

Figure 10 is a front view of the spring or resilient compressor showing the watch case in dotted outline as it would rest on the compressor and the springs before they are compressed.

Figure 11 is an enlarged view of the compressor and showing the watch case with the compressor arms in position to compress the resilient means or springs into the recesses in the outer watch case and showing the inner watch case held in position by the stem rod ready to receive the spring elements into the recesses formed around the surface of the inner watch case.

Figure 12 shows the inner watch case assembled to the outer watch case with the resilient members or springs interposed between the inner and outer watch cases.

My invention resides primarily in the outer watch case 10 which may be formed with a thin modern design and in which I floatingly mount the inner watch case 11, which supports the watch mechanism enclosed within the outer case 10.

The inner case 11 is adapted to receive the watch mechanism 12.

The outer case 10 is formed with a front portion 13 which supports the crystal 14, whereas the back portion 15 closes the outer watch case 10 in the ordinary manner. The body or frame portion

of the outer case 10 extends like a ring and is formed with corner portions 16 in which sockets 17 are formed which are adapted to receive the inner ends of the resilient members 18. The resilient members 18 are in the form of coil springs as illustrated. However, the resilient members may be formed of rubber or other flexible material (not shown in the drawings) to provide a resilient cushioning means extending between the outer case 10 and the inner case 11.

The inner case 11 is formed with a groove 19 which is adapted to receive an annular shoulder formed on the frame of the watch mechanism 12. Thus, when the mechanism 12 is mounted in the inner case 11, the screws 20 are adapted to draw the annular shoulder into the annular groove 19 to form a tight joint between the mechanism and the frame 11.

In one form of the inner case 11, the back is opened, as is illustrated in Figures 2, 3, 5 and 6, so that the mechanism may be readily observed when the back cover 15 of the watch case 10 is removed. In the other form of the inner case 11', the back 21 is closed so that when the watch mechanism 12 is anchored in the cup shaped inner case 11', the shoulder of the mechanism will fit in the annular groove 19 and seal the mechanism in the cup shaped inner case 11' to seal the mechanism from dust and the outer atmosphere.

I provide a recess 22 extending annularly in the case 10 for free movement of the dial face 23 so that as the mechanism is floatingly supported within the outer case 10 by the springs 18, free movement is accorded to the entire mechanism of the watch to prevent any jar or shock against the outer case being transmitted to the inner case and watch mechanism 12.

I also provide a sleeve 24 through which the winding stem 25 of the watch extends freely to permit the floating movement of the mechanism 12 in the outer case 10. I provide the winding cap 26 with a depending shoulder 27 which is spaced from the sleeve 24 and which acts as a guard to prevent dust from entering through the sleeve 24 into the watch case 10. It will appear that I have mounted the watch mechanism 12 in a manner to float within the outer case 10 being supported by the four springs 18, the ends of which are mounted in the recesses 17 in the case 10 and the recess 28 formed in the outer surface of the inner case 11. Further, I have formed the recess 28 in the form of a groove which receives the coil of the spring 18 to hold the same in a set position.

The invention resides in the simple means of mounting the mechanism within the inner casing 11 or 11' with a four point suspension held in place by resilient means of any suitable character. With this construction, I eliminate unnecessary parts and I am able to mount the watch mechanism directly in the inner case 11, which in turn is floatingly supported in the outer case 10. I recognize that it may be desirable to rebuild ordinary watch cases in a manner to floatingly support the mechanism therein, or that it is possible that by means of my method of forming the inner and outer cases, the assembly of the mechanism may be clearly simplified, and, therefore, I have provided a method by which the assembly, as well as the preparing of the inner and outer cases for the resilient members may be easily accomplished. Thus my disclosure includes the method of preparing the inner and outer cases and the assembly of the same in a simple and efficient manner

as defined by the drawings in Figures 7 to 12 inclusive.

In Figure 7 I have illustrated a ring template 30 which forms a common template for the outer case 10, as well as the inner case 11. In Figure 7, I have illustrated the inner case 11 positioned inside the ring template 30 and held in position by a stem rod tool 31 which passes through the hole 32 formed in the inner case 11 for the stem 25 to pass through. Thus, in making the inner case, it is only necessary to drill the stem hole 32 and then by placing the inner case 11 inside the template 30, with the template rod 31 extending through the hole 32, the inner case 11 is held in place in the template ring.

The template ring is formed with a series of holes 33 which are adapted to guide the drill 34 so as to properly locate the recesses 28 in the outer surface of the inner case 11. The inner case 11 may then be removed from the template ring 30. When it is desired to form the recesses 17 in the outer case 10, the template ring 30 is positioned in the outer case 10 and held in place by the stem tool 31, as illustrated in Figure 8, whereupon the method proceeds by inserting the drilling unit A in the position illustrated in Figure 8.

The drilling unit A includes a pair of side members 35 and 36 which extend parallel and are held together by the bolts 37 with the intermeshing gears 38 held between the members 35 and 36. One of the gears 38 is adapted to be driven by the shaft 39 and the other gear 38 drives a drill 40. The unit A is held in the template ring 30 as illustrated in Figure 8 with the spring urged member 41 projecting in one of the holes 33 of the template 30, and the drill 40 projecting in the diametrically opposed holes 33 of the template 30, whereupon the unit A is operated to drill the recess 17 in the case 10.

This operation is repeated until the four recesses 17 have been formed in the outer case.

The method includes the separation of the inner case 11 as heretofore set forth, as well as the outer case 10, and then the springs are adapted to be assembled in the outer case 10, as illustrated in Figures 10 and 11. The method continues by placing the springs 18 in the recesses 17 with a compressor unit B receiving the case 10, as illustrated. The compressor unit B includes a back plate 42 on which the compressor arms 43 are mounted with the free ends of the compressor units being adapted to engage the springs 18, and by means of the cam members 44, the springs 18 are compressed into the recesses 17, which are deep enough to receive the springs, whereupon the inner case 11 is placed in position, as illustrated in Figure 11, with the stem rod 31 holding the inner case 11 in proper position. Then by turning the compressor unit B, the springs 18 are released and automatically spring into the recesses 28 in the outer surface of the inner case, and the assembly of the inner and outer case is complete, whereupon the compressor unit B may be removed and the mechanism 12 of the watch may be mounted in the inner case 11. Thus the assembly, as well as the formation of my watch case, becomes a simple operation carried out by my method and in a simple form of construction which permits a small streamlined watch case to be used for floatingly supporting the watch mechanism therein. The method is important because it permits any properly formed watch case to be readily converted to floatingly support the watch mecha-

nism within the outer casing, and the steps of the method proceed from the making and preparing the inner watch case, which is adapted to receive the watch mechanism, and preparing the outer case so that the resilient members may be interposed between the inner and outer watch case members. The template ring, which is common to both the inner and outer watch case members, insures the proper positioning of the recesses for the resilient member and the drilling unit, together with the compressing unit, merely show a form of means which may be used to carry out the method and to properly form the watch cases employed in supporting and enclosing the watch mechanism.

I claim:

1. A watch case for enclosing the timekeeping mechanism of a watch, including an outer rectangular-like casing having reinforced corner portions, a recess formed within each of said corner portions, an inner casing spaced from said outer casing and having a series of recesses adapted to coincide with said corner recesses, resilient members positioned in the coincident

recesses in said corners and said inner casing to floatingly support said inner casing in relation to said outer casing, said inner casing being adapted to support the timekeeping mechanism of the watch.

- 5 2. A watch case for enclosing the timekeeping mechanism of a watch, including an outer rectangular-like casing having reinforced corner portions, a recess formed within each of said corner portions, an inner casing spaced from said outer casing and having a series of recesses adapted to coincide with said corner recesses, resilient members positioned in the coincident recesses in said corners and said inner casing to floatingly support said inner casing in relation to said outer casing, said inner casing being adapted to support the timekeeping mechanism of the watch, a winding stem projecting into said inner casing, sleeve means anchored in said outer casing and adapted to be spaced from and surrounding said stem, and a winding cap on said stem having a depending flange adapted to extend over the outer end of said sleeve means.

OSCAR GRUBER.
